UNITED STATES PATENT OFFICE.

FRANK YOKEL, OF PHILADELPHIA, PENNSYLVANIA, ASSIGNOR TO WM. B. YOUNG CO.,
OF PHILADELPHIA, PENNSYLVANIA, A CORPORATION OF PENNSYLVANIA.

DESIGN FOR A LAMP COLUMN.

Application filed April 8, 1922. Serial No. 1,644. Term of patent $3\frac{1}{2}$ years.

To all whom it may concern:

Be it known that I, FRANK YOKEL, a citizen of the United States, residing at Philadelphia, in the county of Philadelphia and State of Pennsylvania, have invented a new, original, and ornamental Design for Lamp Column, of which the following is a specification, reference being had to the accompanying drawing, forming part thereof.

The figure shows the lamp column in perspective.

I claim:

The ornamental design for a lamp column, as shown.

FRANK YOKEL.

In presence of—

ANNA M. GORMLEY,
GEO. J. CARMELIA.
